BOOK CONSTRUCTION

Robert C. O'Hair, Sr., Chicago, Ill.

Application November 17, 1933, Serial No. 698,431

7 Claims. (Cl. 281—15)

This invention relates in general to a book construction and is particularly concerned with the arrangement of the leaves and the manner in which the leaves are secured in the book. It is an object of the present invention to provide in a book construction a novel arrangement of leaves whereby certain of the leaves of the book are supported by other leaves of the book and may readily be removed from the book without interfering with the securement of the other leaves in the book.

For purposes of illustration, my invention is illustrated as being utilized in connection with a combination bank deposit book and insurance policy which affords a guarantee to the depositor in accordance with the terms of the policy.

The need for such an instrument as the present invention provides arises in times like the present due to lack of the usual banking facilities, or because of lack of faith in existing banks on the part of prospective depositors. It is intended that the present invention may be advantageously used either by banks or other depositories which do not perform the usual function of a bank but which may under the exigencies of the circumstances existing have been organized to provide the community with a place for deposits.

It is therefore a further object of the present invention to provide an instrument in the nature of a combined bank deposit book and insurance policy, which guarantees the depositor's account, this insurance policy being contained in facsimile on leaves which are removably secured to the other leaves of the book and may be removed when the bank book is turned in due to the failure of the bank or some other exigency which might arise.

The invention also contemplates a removable leaf carried by one of the leaves of the book which contains a waiver of claim against the bank by the depositor. This waiver of claim is likewise detachable from the bank book leaves and may be left attached or may be detached depending upon whether or not the depositor desires to waive his claim.

Other and further important objects of this invention will appear from the disclosures in the specification and accompanying drawing.

This invention (in a preferred form) is illustrated on the drawing and hereinafter more fully described.

On the drawing:

Figure 1 is a plan view of a book embodying the principles of this invention, the book being open to disclose the leaves containing the fac-

simile of the insurance policy for guaranteeing the account;

Figure 2 is a similar view showing the book partially open to disclose the manner in which the leaf containing the waiver form is secured to one of the leaves of the book;

Figure 3 is a view similar to Figure 1 except that the book is open to disclose the leaves wherein deposits, withdrawals, balance, etc., of the particular account may be entered in the usual course of banking business; and

Figure 4 is a transverse sectional view through the book, taken substantially on line IV—IV of Figure 3.

As shown on the drawing:

The reference numeral 10 generally indicates a book, in this instance a bank deposit book, or pass book, embodying the features of the present invention. This book is provided with the usual opposed cover members 11 and 12 which are hinged at their innermost edges in the usual manner.

The book contains a plurality of leaves, the innermost leaves being shorter than the height of the book covers as indicated at 13 and 14. These leaves are disposed between leaves 15 and 16 which project above the leaves 13 and 14 and carry various indicia such as the name of the depositor, the pass book number, etc. The leaves 13 and 14 may be ruled in the usual manner to provide columns for dates, withdrawals, deposits, balance and the like as used in the ordinary deposit book in the course of banking operations. This arrangement enables the account to be carried from one set of short leaves to another set of short leaves as the leaves become filled by the entries of deposits, withdrawals, and the like, without the necessity of having to recopy the general indicia as shown on pages 15 and 16 each time the entries are continued onto a new page.

Between the leaves or pages 15 and 16 and the cover members of the book, the leaves or pages are arranged and secured in a different manner than at present embodied in the usual bank deposit book.

Attention is called to the fact that these pages just referred to are constructed of a single piece of material. Disposed outwardly of leaf 16 is a leaf 17 which extends over the cover member 12 and extends over cover member 11 to form a leaf 18 similar to leaf 15. The midlines of leaves 17 and 18 are secured to the juncture of the cover members in the usual manner, as by stitching 18a.

The free edge of leaf 18 is carried back over the rear surface of leaf 18 to define leaf 19, and is formed into a loop having its closed end 20 disposed adjacent the secured inner edges of leaf

5 18. The other end of this loop, which forms leaf 21, is again turned back to form a leaf 22 which lies against the cover member 11 and is carried over cover member 12 to form a leaf 23. The mid line or juncture of leaves 22 and 23 is secured 10 by the stitching 18a to the cover members.

The outer edge of leaf 23 is turned back over the forward face thereof to form an inwardly extending leaf or flap 24 having its inner or free edge disposed adjacent the line of securement of 15 the leaves to the cover member.

The loop formed by leaves 19 and 21 is secured at its open end as at 25 and 26 to the leaves 18 and 22 respectively by means of perforations 27 and 28 whereby the leaves forming the loop may 20 be detached from the book, when desired. The leaves 19 and 21 may have printed thereon a facsimile 29 of an insurance policy containing terms relating to the guarantee of the depositor. These leaves may also have indicated thereon 25 as shown at 30 the policy number and other data which may be necessary.

As shown in Figure 2, the page 24 may contain the provisions of a waiver of claim by the depositor. The page 24 is secured at its outer 30 edge of the outer edge of page 23 by a line of perforations 31, which enable the waiver of claim to be readily torn out of the book when the depositor desires to waive his claim.

It will be appreciated from the foregoing description that the present invention is not confined to use in connection with bank books, but is of universal application and may be advantageously used in many types of books. It will therefore be apparent that the present invention 35 provides a novel arrangement of leaves in a book, these leaves being secured in such a manner as to enable the ready removal of certain of the leaves without interfering in any way with the securement of the other leaves of 40 the book or the indicia or other matter contained thereon; a book in which the leaves are so arranged that it is particularly advantageous when used in connection with a combination bank book and insurance policy containing the terms for 45 guaranteeing the depositor.

I am aware that many changes may be made and various details of construction may be varied through a wide range without departing from the principles of this invention, and I, therefore, do not purpose limiting the patent granted otherwise than necessitated by the scope of the 50 appended claims.

I claim as my invention:

1. In a book construction, a sheet folded to form 60 four consecutive leaves, the two outermost leaves having their inner margins bound together, and the two innermost leaves having their inner margins integrally joined and their outer margins respectively secured to the outer margins of the 65 outermost leaves.

2. In a book construction, a sheet folded to form 65 four consecutive leaves, the two outermost leaves

having their inner margins bound together, and the two innermost leaves having their inner margins integrally joined and their outer margins respectively joined to the outer margins of the outermost leaves, and tear lines at the jointures 5 of the innermost leaves with the outermost leaves, whereby the innermost leaves may be removed as a unit.

3. A book of the character described comprising a plurality of leaves, and a pair of adjacently disposed double leaves defining two sections, each of said leaves forming two pages with the creased line forming the outer edges of both pages, the inner margins of the outermost sections being bound together and the inner margins of the 15 innermost sections being integrally joined and disposed contiguous the binding of the outer sections, and perforations on said creased lines to enable removal of the innermost sections as 20 a unit.

4. In a book construction a pair of contiguous leaves having their inner margins bound together, the outer margins of said leaves being inwardly deflected and joined to form a single loop and define confronting pages, the closed end of 25 the loop being disposed adjacent the bound margins of said leaves, whereby the surfaces of the confronting pages may be perused without the necessity of unfolding the inwardly deflected portions beyond the outer edges of the leaves of the 30 book, and tear lines whereby the inwardly deflected portions and the matter thereon may be bodily removed.

5. A book construction including a cover and a pair of leaves having their inner margins secured to the cover, said leaves being extended inwardly from their outer margins to form a single loop portion having a closed inner end disposed adjacent the securement of the leaves, said loop portion lying within the confines of the book 40 leaves, and a weakened connection at the jointure of the loop portion with the leaves.

6. A book of the character described comprising a plurality of double leaves, said leaves being secured at their center line to form book pages, 45 a sheet having its outermost edges detachably secured to the outermost edges of two of said leaves and a central fold line disposed adjacent the securement of said leaves to form removable pages co-extensive with the pages formed by the 50 said leaves.

7. In a book construction, a pair of superposed double leaves secured at their center line to form book pages, a double leaf having a central fold line disposed adjacent the securement of said 55 pair of double leaves and having its outermost edges respectively connected along tear lines to the outermost edges of two of the similarly disposed leaves of said pair, and a single leaf having an edge connected along a tear line to an outermost edge of one of the other two similarly disposed leaves of said pair and normally lying with its free edge disposed between said pair adjacent their securement, all of said leaves being embodied in a single sheet of material. 65
